UNITED STATES PATENT OFFICE

97,084

DESIGN FOR A MILK TRUCK

Daniel S. McGuire, Chicago, Ill., assignor to Beloit
Dairy Co., Chicago, Ill., a corporation of Illinois

Application November 30, 1934, Serial No. 54,198

Term of patent 7 years

To all whom it may concern:

Be it known that I, Daniel S. McGuire, a citizen of the United States, residing at Chicago, in the county of Cook and State of Illinois, have invented a new, original, and ornamental Design for Milk Trucks, of which the following is a specification, reference being had to the accompanying drawings forming a part thereof.

Figure 1 of the drawings is a side perspective view of a milk truck embodying my new design; and

Figure 2 is a rear perspective view.

The dominant and essential features of the milk truck design are shown in full lines in the

drawings and comprehend an undercut or recessed part in the lower portion of the back of the truck with a platform extending rearwardly therefrom and a balustrade around the platform, and the appearance produced by fixing on the platform within the balustrade a front and a rear row of milk cans with the cans of the front row partially disposed within the undercut part and the cans of the back row in staggered relation with respect to those of the front row.

I claim:

The ornamental design for a milk truck, substantially as shown and described.

DANIEL S. MCGUIRE.
